[57] CLAIM

The ornamental design for a fireplace shovel, as shown and
described.

DESCRIPTION

FIG. 1 is a front perspective view of a fireplace shovel,
showing my new design;

FIG. 2 is an enlarged front elevational view thereof;

FIG. 3 is an enlarged rear elevational view thereof;

FIG. 4 is an enlarged bottom plan view thereof;

FIG. 5 is an enlarged top plan view thereof; and,

FIG. 6 is an enlarged side elevational view thereof, the
opposite side being a mirror image of that shown.
